UNITED STATES PATENT OFFICE.

LYNTON D. WYANT, OF TULSA, OKLAHOMA.

OIL-CRACKING AND CARBON-REMOVING METHOD AND APPARATUS.

Application filed March 20, 1922. Serial No. 545,275.

To all whom it may concern:

Be it known that I, LYNTON D. WYANT, a citizen of the United States, residing at Tulsa, in the county of Tulsa and State 5 of Oklahoma, have invented new and useful Improvements in Oil-Cracking and Carbon-Removing Methods and Apparatus, of which the following is a specification.

This invention relates to a method of 10 and apparatus for cracking hydrocarbon oils and removing coke or carbon therefrom during the cracking operation.

The process of heating heavy hydrocarbon oils to high temperatures, thus causing 15 the decomposition of heavy molecules into molecules having lower boiling points than the original heavy oils, is generally called "cracking".

This cracking operation is carried on by 20 various processes, all of which are faced by the same general problem of the elimination of the carbon which is precipitated or which remains in the distillation system when heavy hydrocarbons are cracked to 25 yield lighter oils.

When a large volume of oil is heated to high temperatures, say 600° F. to 800° F., under pressure of from 75 lbs. to 150 lbs. 30 per square inch, there is a considerable danger hazard. These temperatures are so high as to render the tensile strength of the metal of which the still is composed very much reduced. This trouble is very much increased because of the free carbon deposited in the still. Divers means are now employed to keep this free carbon, which 35 is a good non-conductor of heat, from depositing on the still bottom. Of these devices there are many now in use, such as 40 chain drags, double bottoms, helicoidal scrapers, etc., but with these separate or combined devices the amount of oil that can be distilled or cracked is limited to 45 from 40% to 60% of the still capacity. 50 Many of the devices suggested are not practical because they are too complicated to be operated in the still at such high temperatures. But with the best means that 55 are at present employed only a maximum of about 60% of the still capacity can be distilled or cracked before the still has to be taken down or shut down and the carbon deposited therein be removed therefrom before the process can be resumed or continued.

One object of this invention is to provide a simple and practical method of and means for eliminating carbon accumulations from a cracking still while the still is in operation, thereby increasing the 60 amount of the material that can be cracked before the still has to be shut down in order to prevent hot spots from forming. Hot spots form on a still bottom because the percentage of free carbon in the residuum oil in the still becomes so great 65 that the agitation given the oil by its boiling, and by means of drags and scrapers now in use, will not prevent such an amount of carbon from being deposited on the still bottom as to insulate the oil from the heat and materially interfere with the heat transmission from the still shell to the body of oil, thereby causing the metal of the still shell to become red and rendering any further operation of the still dangerous until the carbon deposits are removed. 70

A further object of the invention is to provide a simple, reliable and efficient method of and means for removing the free 80 carbon from the oil whereby, in addition to the time period of cracking being materially lengthened, the incrustation of carbon upon the still bottom will be materially reduced, thus enabling the still to be 85 cleansed when necessary with greater ease and with a considerable saving of time, and thus reducing the shut down periods between successive cracking operations.

In the accompanying drawings illustrating the invention, 90

Figure 1 is a vertical longitudinal section through a cracking still embodying the invention, and

Figure 2 is a vertical transverse section 95 through the still.

Referring to the drawings, 1 designates a horizontally disposed still, which in general may be of any ordinary form, size and construction, which still is provided with the usual vapor collecting dome 2, from which the vapor flows through the vapor line 3 to the "knock-back" tower 4, and thence through a pipe or conductor 5 containing a pressure relief valve 6 to the condenser (not shown). 7 is the return line for the return of any oil separated in the tower from the vapors, for the flow of said oil back to the still, and 8 is a pressure gage of any suitable type or construction. The still may be ini- 110

tially charged from a source of supply by gravity or through the action of a pump, and a pump or other suitable supply connections may be employed for replenishing the still at intervals during the cracking period. Also any suitable means may be employed for emptying the still of any residuum oil when run is completed. I have not deemed it necessary to show any type of oil supplying or residuum discharging connections, as such specifically constitute no part of the present invention, and as any of the devices in common use for these purposes may be employed.

In accordance with my invention, the lower portion of the tank is sub-divided by a vertical transverse partition 9 to form a heating and agitating chamber 10 and a settling chamber 11, the former being of materially greater length than the latter. The chamber 10 is designed to be heated at its bottom from a suitable type of furnace below, 12 indicating the back fire wall of the furnace, which is arranged substantially in vertical alinement with the partition, the chamber 11 thus being arranged beyond the line of the furnace so that the contents thereof will not be directly heated therefrom. 13 indicates a thermometer well communicating with the bottom of the chamber 10 and leading to any suitable type of thermometer or heat indicating device, whereby the temperature of the oil in the bottom of said chamber may be determined at any time, and 14 designates the outlet leading from the bottom of the chamber 11 for the discharge of the gathered coke or carbon therefrom. This outlet 14 is preferably funnel-shaped or diametrically contracted toward its discharge end and is provided with a discharge nozzle 15 having a controlling valve 16 which may be opened whenever it is desired to effect the discharge of the gathered carbon.

In practice the still is charged with oil in the usual manner to a suitable level above the maximum oil level $x-x$ indicated in Figure 2, the excess of oil being such that when 20% of the oil being cracked is distilled out of the still the remaining 80% will fall below the level of the line $x-x$, the oil being maintained, during the cracking process, between the said maximum level $x-x$ and the minimum level $y-y$, also indicated in Figure 2. The supply of oil is replenished from time to time, by pumping in fresh charges as the vapors are taken off through the vapor line 3, so as to generally maintain the higher level noted. The oil in the still after 20% has been cracked contains all the free carbon produced by the cracking of the said 20% and this free carbon is suspended in the oil because of the upward agitation of the oil caused by the applied heat and also because of the agita-

tion produced by the mechanical agitators customarily in use. In order to collect and carry off this free carbon and the carbon which is thereafter liberated during the cracking process, I provide a novel type of separating and collecting means and means for keeping the oil in the bottom of the chamber 10 agitated to maintain the carbon, as far as possible, in suspension and to prevent the deposit of any material amount on the bottom of said chamber.

Extending longitudinally and horizontally within the still is a shaft 17 having affixed thereto and depending therefrom an agitator carrying frame comprising a series of inverted substantially V-shaped brackets 18, the arms of which project beyond opposite sides of the line of the shaft and are connected and reinforced by braces 18'. Secured to the lower ends of these arms is an arcuate or segmental, approximately quadrant, open work or screen agitator 19, composed of chains, iron bars or mesh work material, the convex lower face of which agitator is arranged in close proximity to the bottom of the chamber 10. The shaft 17 is journaled at its rear end in a suitable bearing 20 and extends at its forward end outwardly through a stuffing-box 21, and this outer end of the shaft may be coupled to any suitable means for rocking the shaft for oscillating the agitator 19 laterally back and forth in the chamber 10, the screen thus causing the liberated carbon particles to be kept in motion and in suspension and acting as a scraper or sweeper to keep the bottom of the still chamber as far as possible clear of deposits. At suitable intervals along its length the shaft 17 is also journaled in fixed bearings 22 supported by hanger rods 23 from the still body, and said bearings and hangers also assist in supporting the weight of the agitator, as will be readily understood.

Arranged longitudinally in the still, and also supported by the shaft 17, bearings 22 and hangers 23, is a collecting trough 24, which may be suitably secured at its forward end to the forward end or head of the still, as indicated at 25. This trough is arranged slightly above the maximum oil level line $x-x$ and is provided at its rear end with a discharge opening 26 communicating with settling chamber 11. Disposed at opposite sides of the trough and depending therefrom are carbon collecting pipes or tubes 27, which communicate at their upper ends with the trough and at their lower ends are provided with enlarged portions or collecting funnels 28, said funnels having their lower open ends arranged on opposite sides of the normal medial line of and close to the top surface of the agitator or scraper 19. The said pipes and funnels serve in the nature of jet devices or suction collectors, for draw-

ing the free carbon settling in the chamber 10 and conveying the same to the trough 24 or to the settling chamber 11. It will be understood that the oil by gravity seeks in the pipes 27 and funnels 28 the level of the oil outside the pipes and funnels. The funnels 28 collect the gas, which is evolved because of the heat applied to the still bottom beneath the funnels, over an area considerably in excess of the area of the pipes 27. This gas thus entrapped seeks the surface of the liquid by the natural upward course which forces it into and through pipes 27, and these rising and expanding gases impregnate and make the oil within the pipes lighter than the oil outside the pipes, which is not so highly impregnated with gases, thus causing the entrapped gases to eject an amount of oil into the trough 24, portions of the oil thus being constantly drawn into the pipes and ejected therefrom by pressure, difference in weight, velocity and suction into the trough. This action is constant during the cracking process because the oil inside the funnels continues to rise in the pipes to the level of the oil outside the funnels. The liquid thus carried over into the trough 24 is higher than the natural level of the oil in the still and carries with it its relative amount of free carbon and this oil flows along the trough to the outlet 26 and thence into the settling chamber 11, carrying with it the suspended free carbon which it contains.

As hereinbefore stated, the settling chamber 11 is separated from the heating and agitating chamber 10 by the intervening partition 9 and the oil contained therein is not heated and directly subjected to boiling agitation, nor by the action of any agitator or scraper, and hence the body of oil contained in the chamber 11 is comparatively quiet or free from bubbling or other similar motion. Thus it will be understood that the oil and carbon discharged from the trough into the body of oil in the chamber 11 comes comparatively to a state of rest, as a result of which the collected carbon deposits contained therein settle by gravity into the outlet 14, from which the carbon collected may be discharged whenever desired by opening the valve 16. To further assist in making the flow of oil as quiet as possible in the chamber 11 a vertically disposed baffle plate 29 is disposed therein substantially on a vertical line between the partition 9 and the axial center of the outlet 14, said baffle plate extending to a point somewhat above the maximum liquid level line $x-x$. This partition plate prevents a direct back current or flow of the oil over the partition 9 and any movement of the oil in the chamber 11 tending to disturb its comparative degree of stillness. As the carbon accumulates in the outlet 14 and

chamber 11, however, the body of oil contained therein, from which the carbon has been precipitated, will rise and flow back under and or around the baffle 29 and over partition 9 into the chamber 10, so that such oil will be subjected to the intense heat required in the latter-named chamber for the cracking action.

It will be understood from the foregoing description that through the agitation of the oil contained in the chamber 10 from the heat, and the movement of the agitator 19, substantially all or a greater proportion of the liberated carbon in such chamber will be kept in suspension, which action will be further promoted by the additional agitation of the jetting of the oil and carbon through the pipes 27 into the trough 24 and the constant relief of heavy deposits from the body of oil in said chamber by the drawing off of the carbon deposits therefrom. By this means a considerable proportion of the carbon will not only be removed and discharged from the body of oil, but the deposit of the carbon on the surface of the bottom of the chamber 10 will be retarded and to a large extent prevented, thus keeping the heated bottom portion of the still free from carbon deposits for a longer period with the result that the cracking operation may be carried on for a much longer period of time. This operation also reduces the depth, thickness and degree of hardness of the carbon deposits on the bottom, with the result that, when it is necessary to shut down the still for cleaning purposes, the carbon may be removed with greater ease and facility and within a less period of time, thus shortening to a considerable extent the shutting down period. Experience has demonstrated that a still of this character embodying my improvements may be operated at a working pressure of from 75 to 150 lbs. per square inch, and under a temperature of from 600 to 850° F., with much greater safety than stills of ordinary construction, owing to the fact that from 80% to 125% of the still volume can be run without danger of red spots.

Having thus fully described my invention, I claim:

1. The process of cracking oil and separating carbon therefrom which consists in heating the oil under a pressure of 70 to 100 pounds per square inch to cracking temperature, agitating the heated oil to maintain the liberated carbon more or less in suspension within the oil, and continually segregating and discharging streams of this oil impregnated with carbon from the heated portion of the still under the direct action of gas pressures generated in the still and then discharging such carbon impregnated oil to a place within the still where such carbon can be settled out and removed.

2. The process of cracking oil and removing carbon therefrom, which consists in heating a body of oil to cracking temperature, agitating the heated oil to maintain the liberated carbon more or less in suspension, ejecting portions of oil containing charges of carbon from the body of heated oil through pressure directly generated through the gases present in and as evolved from the body of oil and then separating the charges of carbon from the oil within the still and discharging the carbon so collected.
3. The process of cracking oil and removing carbon therefrom, which consists in heating a body of oil, mechanically agitating the same to maintain more or less of the liberated carbon in suspension, collecting streams of the evolved gases as evolved in the body of oil, causing said streams of gases to segregate and eject from the body of oil portions of oil containing portions of the suspended carbon, and then separating and discharging the carbon.
4. The process of cracking oil and separating carbon therefrom, which consists in heating and agitating a body of oil, ejecting by pressure produced by evolved gases from the body of oil as evolved portions of oil carrying portions of the carbon, and then collecting and discharging the carbon.
5. The process of cracking oil and removing carbon therefrom, which consists in directly heating and agitating a portion of a body of oil, under a pressure of 70 to 100 pounds per square inch, to a temperature of from 600° F. to 800° F., while maintaining said portion of said body of oil separated from a relatively quieter portion of oil also under the same pressure conditions and of the same body, producing jets from the gases evolved from the heated and agitated portion of the body of oil and causing said jets to eject from said heated portion of the body of oil streams of oil carrying portions of carbon with them, collecting and conducting the ejected streams of oil and carbon carried thereby to the relatively quieter portion of the body of oil, allowing the carbon to settle out in said relatively quiet portion of the body of oil, and then discharging the collected carbon.
6. The process of cracking or distilling oil and collecting and separating carbon therefrom, which consists in providing a still having a heating and agitating chamber and a settling chamber, heating and agitating the oil in the heating and agitating chamber while allowing the oil in the settling chamber to remain in a comparatively quiescent state, collecting columns of evolved gases from the bottom of the heating and agitating chamber, causing said columns of gases to draw and eject from the body of oil in the heating and agitating chamber to a level above said body of oil streams of such oil with particles of free carbon, collecting and conducting the ejected oil and particles of carbon to the settling chamber, causing the carbon so collected to be precipitated in the settling chamber, and then discharging the gathered carbon.
7. The process of cracking oil and removing carbon therefrom, which consists in directly heating and agitating one portion of a body of oil while maintaining another portion of the same body of oil more or less remote from the source of heat and in a comparatively quiet state, collecting gases evolved from the heated and agitated portion of the oil and under the pressure thereof causing jets or streams of oil to be ejected from the said heated and agitated portion of the oil together with portions of carbon carried thereby, collecting and conducting the ejected streams of oil and carbon carried thereby to the relatively quieter portion of the body of oil, allowing the carbon to settle in said relatively quiet portion of the body of oil, and then discharging the collected carbon.
8. The process of cracking oil and removing carbon therefrom, which consists in heating and mechanically agitating a portion of a body of oil, under a pressure of 70 to 100 pounds per square inch, to a temperature of from 600° F. to 800° F., while maintaining said portion of said body of oil separated from a relatively quiet portion of oil also under the same pressure conditions and of the same body, producing jets from the gases evolved from the heated and agitated portion of the body of oil and causing said jets to eject from said heated and agitated portion of the body of oil streams of oil carrying portions of carbon with them, collecting and conducting the ejected streams of oil and carbon carried thereby to the relatively quiet portion of the body of oil, allowing the carbon to settle out in said relatively quiet portion of the body of oil, and then discharging the collected carbon.
9. The process of cracking oil and removing carbon therefrom, which consists in maintaining two portions of the same body of oil separate while permitting flow of oil from one portion to the other when the oil of either portion rises above a predetermined level, heating and mechanically agitating one portion of the body of oil while maintaining the other portion of the body of oil in a comparatively quiet state, producing streams of gases from the gases evolved from and in the heated and agitated portion of the body of oil, causing said streams of gases to force segregated streams of oil from the heated and agitated portion of the body of oil to a level above the normal level of such portion of the body of oil, such streams of gases and oil carrying with them their proportions of the carbon contained in the heated and agitated portion of the body of oil, collecting the ejected oil streams and carbon above the level of the heated and

agitated portion of the body of oil and conveying the same to the relatively quiet portion of the body of oil, permitting precipitation of the carbon in the comparatively quiet portion of the body of oil, and then discharging the collected carbon therefrom.

10. The process of removing carbon from the oil during distillation, which consists in heating the oil to cracking temperature and pressure while mechanically agitating the same to keep the free carbon more or less in suspension therein; collecting from the oil evolved gases and causing the same to travel upwardly in segregated streams 15 through the body of oil, causing said streams of gases to carry with them portions of the oil in the form of streams carrying with them entrained portions of carbon and discharging the same at a point above the 20 level of the body of oil, and then collecting the streams of oil and discharging the carbon therefrom.

11. An oil cracking still having a heating and agitating chamber and a settling chamber for jointly containing a body of oil, means for separating portions of the body of oil in the heating and agitating chamber and the settling chamber from each other, while permitting oil to flow from one to the 30 other when the oil in either chamber rises above a predetermined level, means for heating and mechanically agitating the portion of the body of oil in said agitating and heating chamber, conductors submerged in 35 the portion of the body of oil contained in the heating and agitating chamber for collecting evolved gases and causing, under the pressure of said gases, the segregation of streams of oil from said portion of the body 40 of oil, together with the carbon carried thereby, to a level above the level of such portion of the body of oil, a collector arranged to receive the streams of oil and carbon carried thereby and convey the same to the oil contained in the settling chamber, and means for discharging the carbon from 45 the settling chamber.

12. An oil cracking still having a heating and agitating chamber, means for agitating the heated oil in said chamber, means for producing gas forces from the gases evolved from the heated oil, means for directing and causing said gas forces to eject streams of oil from the body of oil in the chamber with 50 portions of carbon carried thereby, and means for separating the carbon from the ejected streams of oil and discharging such carbon from the still.

13. An oil cracking still having a heating and agitating chamber, means for agitating the body of oil in said chamber, a collector arranged above the level of the oil, conductors depending into the body of oil for the collection of evolved gases and upflow there- 60 through into said collector of portions of

the oil and portions of carbon carried thereby by the pressure of said gases, and means for separating the carbon from the oil ejected into the collector and discharging the separated carbon from the still.

70

14. An oil cracking or refining still having a heating and agitating chamber, an agitator operating in said chamber, a collecting trough arranged above the normal level of the oil, conductors depending into the body of oil and communicating at their upper ends with the trough for the collection of evolved gases and the upflow of portions of oil and portions of carbon into the trough from the body of heated oil under pressure of said gases, and means for separating the carbon from the oil and discharging the same from the still.

80

15. An oil cracking still having a heating chamber and a settling chamber, a partition separating said chambers, means for heating the heating and agitating chamber separate from the settling chamber, a discharge outlet from the settling chamber, a collecting trough arranged above the normal level of the oil and having an outlet for discharge into the settling chamber, and pipes communicating at their upper ends with the trough and having enlarged portions at their lower ends depending into the body of oil in the heating and agitating chamber at a point near the bottom of said chamber, for collecting streams of evolved gases and under the action thereof forcing portions of the oil and particles of carbon into the trough.

95

16. A cracking still having a heating and agitating chamber and a settling chamber, agitating means in said heating and agitating chamber, means for producing gas forces from the gases evolved from the heated oil, means for directing and causing said gas forces to eject streams of oil from the body of oil in said heating and agitating chamber with portions of carbon carried thereby, conducting the ejected streams of oil and the carbon carried thereby to said settling chamber, and means for discharging the collected carbon from the settling chamber.

105

17. An oil cracking still having an agitating chamber and a settling chamber, means for agitating the oil in the agitating chamber to keep the liberated carbon in suspension, means acting under pressure generated in said chamber for jetting portions of the liquid, with portions of carbon carried thereby, from the agitating chamber and conveying the same to the settling chamber, and means for discharging the collected carbon from the settling chamber.

115

18. In an apparatus for cracking hydrocarbon oil and removing carbon therefrom, means for heating a body of oil, means for mechanically agitating the same to maintain the carbon more or less in suspension, means acting under pressure of the gases evolved 120

125

130

in the cracking operation to force streams of oil, carrying with them proportions of carbon, from the body of oil, and means for collecting and discharging the carbon so separated from the body of oil.

19. A cracking still having a heating and agitating chamber and a settling chamber, said chambers being adapted to contain portions of a body of oil contained in the still, a partition for separating said portions of the body of oil from each other while permitting overflow of oil from one chamber to the other, means for heating the portion of the body of oil contained in the heating and agitating chamber, means for mechanically agitating the portion of the body of oil contained in said heating and agitating chamber, upwardly extending conductors in said heating and agitating chamber for collecting gases evolved from the portion of the body of oil therein and causing streams of such gases to pass upwardly therethrough and to carry with them streams of oil and proportions of carbon carried thereby, and a collector arranged above the level of the body of oil to receive said streams of oil and carbon and convey the same to the settling chamber.
20. An oil cracking still having a heating and agitating chamber and a settling chamber, said chambers being adapted to contain portions of the same body of oil, means for separating the portions of the body of oil contained in said chambers while permitting oil to overflow from one chamber to the

other, means for heating the portion of the body of oil contained in the heating and agitating chamber, an agitator for mechanically agitating the portion of the body of oil contained in said heating and agitating chamber, conductors extending upwardly through the portion of the body of oil in the heating and agitating chamber and extending above the level thereof, said conductors having enlarged lower ends for collecting evolved gases and causing upflow to a level above the top of the said portion of the body of oil, a collector for receiving the ejected streams of oil and carbon and conveying the same to the settling chamber, a vertically disposed baffle plate in the settling chamber extending upwardly to a point slightly above the level of the partition, and a valved discharge outlet from said chamber.

21. In an apparatus for cracking hydrocarbon oil and removing carbon therefrom, a still, means for heating a body of oil contained therein, means for mechanically agitating the oil to maintain the carbon more or less in suspension, means for collecting evolved gases from the body of oil and under the pressure thereof, segregating and ejecting streams from the oil carrying with them portions of the suspended carbon, and means for collecting the carbon carried by the streams of oil and discharging the same from the still.

In testimony whereof I affix my signature.

LYNTON D. WYANT.
